UNITED STATES PATENT OFFICE

HARRY E. CROSBY, OF WALNUT PARK, CALIFORNIA, ASSIGNOR TO MISSION DRY CORPORATION, LTD., OF LOS ANGELES, CALIFORNIA, A CORPORATION OF DELAWARE

DESIGN FOR A DISPENSER

Application filed August 30, 1930. Serial No. 36,827. Term of patent 3½ years.

To all whom it may concern:

Be it known that I, HARRY E. CROSBY, a citizen of the United States, residing at Walnut Park, in the county of Los Angeles and State of California, have invented a new, original, and ornamental Design for Dispensers, of which the following is a specification, reference being had to the accompanying drawings, forming part thereof.

Figure 1 is a front elevation, and Figure 2 is a top plan view on a reduced scale showing my new design.

I claim:

The ornamental design for a dispenser, as shown.

HARRY E. CROSBY.
